Primary Examiner — Brett Miller*Assistant Examiner* — Nader Abadir(74) Attorney, Agent, or Firm — NKL LAW; Jae Youn Kim(57) CLAIM

I claim the ornamental design for a wine glass, as shown and described.

DESCRIPTION

FIG. 1 is a perspective view of a wine glass, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings show portions of the wine glass that form no part of the claimed design.

1 Claim, 6 Drawing Sheets(56)
